CLEANSING COMPOSITION

Emil T. Hinkel, Jr., Bethlehem, N.Y., assignor to Sterling Drug Inc., New York, N.Y., a corporation of Delaware
No Drawing. Filed Dec. 8, 1965, Ser. No. 512,520
3 Claims. (Cl. 252—106)

This application is a continuation-in-part of the co-pending Hinkel Jr. application, Serial No. 331,908 filed December 19, 1963, and now abandoned.

This invention relates to an antibacterial sudsing detergent. More particularly the invention is concerned with an improvement in non-soap cleansing compositions of the type described in United States Patent 2,303,932.

The compositions described in the above-mentioned patent have met with outstanding success for over a decade as fast-acting, thorough, personal cleansing agents in hospitals and homes. More recently, such compositions with added hexachlorophene or bis(2-hydroxy-3,5,6-trichlorophenyl)methane have been of special value to operating room teams, surgical patients, hospital personnel and others coming in contact with pathogenic bacteria. These compositions are more efficient and more rapid in action than are the age-old soaps which, because of their inherent alkalinity, are, among other things, irritating to the skin and ineffective in acid media.

Compositions with hexachlorophene made according to the teaching of the above patent have the same pH as normal skin and hence, rather than removing the normal acid mantle of the skin as does soap, actually deposit an emollient antiseptic film which can be built up and maintained by continued use. The compositions can therefore be used as brushless scrubs in preparing both the skin of a patient as well as the surgeon's hand for operation. Repeated and extensive studies have shown these preparations to be as efficacious in eliminating skin bacteria as preparations requiring three times as much time while greatly lowering the incidence of skin irritation.

The above-mentioned compositions do, however, have certain inherent deficiencies which, in particular instances, rule out their use.

Certain gram-negative organisms, particularly of the coliform and pseudomonas groups, are common contaminants of the skin and other surface areas susceptible to the application of antibacterially active detergent compositions. It is therefore important to reduce or eliminate these organisms along with the gram-positive organisms such as cocci to attain and maintain minimal bacterial contamination. However, antibacterial agents which have been used in combination with detergents of various types, while having in certain instances some effect on gram-negative organisms, require either an irritatingly high concentration or too long an exposure time. For example, the following representative antibacterial agents when added to hexachlorophene-containing compositions prepared as described in the above-mentioned patent gave preparations which were either ineffective or effective only at high concentrations against gram-negative organisms such as *E. coli* and *Ps. aeruginosa*: benzoic acid and its derivatives such as salicylic, 4-methylbenzoic, 4-chlorobenzoic and 3,4-dichlorobenzoic acids; benzyl alcohol and its derivatives such as 3,4-dichlorobenzyl and 2,4-dichlorobenzyl alcohols; phenols such as o-phenylphenol, 4-chloro-2-propylphenol, 4-chloro-2-hexylphenol,

2

4-chloro-3,5-dimethylphenol and bis(2-hydroxy-5-chlorophenyl)methane; and halosalicylanilides such as 3,4,4'-trichlorocarbanilide, 3,5,3',4'-tetrachlorosalicylanilide and 5-chloro-4'-nitrosalicylanilide.

In accordance with the present invention, there are provided stable, sudsing, non-soap cleansing preparations which exhibit a high level of antibacterial activity against gram-negative organisms while retaining gram-positive antibacterial activity. The new compositions consist of aqueous emulsions of the type described in U.S. Patent 2,303,932 optionally but preferably containing hexachlorophene and, according to the present invention, also containing a halogenated salicylic acid of the general formula

wherein X is a halogen and therefore including fluorine, chlorine, bromine and iodine and n is a number from 1 to 3. The compounds are members of a known class and generally are prepared by the nuclear halogenation of salicylic acid or by replacement by halogen of the diazotized amino group of an aminosalicylic acid.

The preferred compounds in the general class are the monohalogenated salicylic acids exemplified by 5-bromosalicylic acid, 3-fluorosalicylic acid, 6-chlorosalicylic acid and 4-iodosalicylic acid with the 5-bromosalicylic acid being especially preferred. The dihalogenated salicylic acids exemplified by 3,5-difluorosalicylic acid, 3,5-dichlorosalicylic acid, 3,5-dibromosalicylic acid and 3,5-diiodosalicylic acid, while exhibiting slightly higher antibacterial activity, are less desirable in certain instances because of their slow in vivo metabolism. The amount of the halogenated salicylic acid can be varied somewhat but ordinarily it is preferred to employ 0.1-1.0% by weight.

The emulsion to which the halogenated salicylic acid is added includes an anionic detergent of the alkylphenoxy-polyalkylene ether sulfonate type, petrolatum, lanolin, or other conventional oleaginous base materials, thickening agents, preservatives, etc.

The alkylphenoxy-polyalkylene ether emulsifying agents useful in practising the invention are the surface active agents described in U.S. Patent 2,115,192, issued April 26, 1938 which are prepared by condensing an alkylphenol with a dihalopolyalkylene ether and reacting the product obtained with a metal sulphite. Particularly useful alkylphenoxy-polyalkylene ether sulfonates for the purposes of this invention are the p-tertiary octylphenoxy-polyalkylene ether sulfonates produced by condensing p-tertiary octylphenoxy-polyalkylene ether halides with a metal sulfite. A preferred compound of this group is the product containing three ether groups per p-tertiary octylphenyl nucleus, an approximately 28% aqueous dispersion of which is known under the name "Triton X-200" and also under the designation "Entsufon."

The alkylphenoxy-polyalkylene ether sulfonate is used in amounts from 10% to about 20% by weight in the compositions. Ordinarily, for general use it is preferable to use about 14% by weight of the sulfonate although in particular circumstances higher or lower percentages may be more useful.

The remaining major constituent of the emulsion is, of course, water which generally is present in amounts ranging from 60% to 80% by weight along with preservatives, smoothing agents, emulsifiers, chelating agents and other conventional pharmaceutical excipients.

The emulsion when ready for use is at a pH of 5-6, preferably pH 5.5, the pH of the skin, as attained by conventional addition of acid, e.g. hydrochloric, or base, e.g. sodium hydroxide, as required.

The germicidal efficiency of the compositions of the invention against certain organisms particularly *S. aureus*, *Ps. aeruginosa* and *E. coli*, was determined by a modification of the survival on exposure test described by Weber and Black, Am. J. Pub. Health 38, 1405 (1948). In this procedure the compositions were diluted 1:5 w/w with sterile water and 10 ml. aliquots of the diluted formulation were inoculated with 0.1 ml. of buffer suspension of an appropriate agar slant culture at room temperature. At predetermined time intervals a one milliliter portion of the inoculated formulation was removed and plated on a tryptone glucose extract lecithin agar and incubated for 48 hours at 37° C. The number of organisms on each plate was then determined in the usual way.

The following examples will further illustrate the invention without the latter being limited thereto.

Example 1

A sudsing detergent was made up according to the following formula:

	Percent by weight (w/w)
Triton X-200	50.00
Methylcellulose Gel, 4%	0.75
Hexachlorophene	3.00
Polyethylene Glycol 400	5.50
Monostearate Coconut fatty acid-ethanolamine condensate	1.00
Petrolatum, White	7.00
Water-in-oil emulsifier containing free cholesterol and cholesterol esters	0.70
Hydrochloric Acid ¹	q.s.
Water, deionized, q.s. ad	100.00

¹ Sufficient acid to adjust to pH 5.5.

Example 2

The composition of Example 1 was modified by the addition of 0.03 mole (0.67% by weight) of 5-bromosalicylic acid.

Example 3

The composition of Example 1 was modified by the addition of 0.01 mole (0.22% by weight) of 5-bromosalicylic acid.

Example 4

The composition of Example 1 was modified by the addition of 0.031 mole (0.67% by weight) of 3,5-dibromosalicylic acid.

Example 5

The composition of Example 1 was modified by the addition of 0.01 mole (0.3% by weight) of 3,5-dibromosalicylic acid.

Example 6

The composition of Example 4 was modified by the omission of hexachlorophene, i.e. the composition of Example 1 modified by addition of 0.031 mole of 3,5-dibromosalicylic acid and omission of the 3% hexachlorophene.

The following comparative tests illustrate the increased gram-negative antibacterial activity of the compositions of the present invention. Tables I and II show the results

obtained using the compositions of Examples 2 and 3 and 4 and 5 respectively on the gram-negative organisms *E. coli* and *Ps. aeruginosa* compared with the composition of Example 1.

TABLE I

Time following exposure (min.)	Number of survivors/ml. following exposure to—					
	<i>E. coli</i> (74×10 ⁶ /ml.)			<i>Ps. aeruginosa</i> (103×10 ⁶ /ml.)		
	Ex. 1	Ex. 2	Ex. 3	Ex. 1	Ex. 2	Ex. 3
10	tnc*	tnc	tnc	tnc	44,400	tnc
	tnc	42,500	tnc	tnc	210	50,800
	tnc	5,700	3,500	tnc	<10	4,500
	tnc	<10	<10	tnc	<10	40

*Too numerous to count.

TABLE II

Time following exposure (min.)	Number of survivors/ml. following exposure to—					
	<i>E. coli</i> (74×10 ⁶ /ml.)			<i>Ps. aeruginosa</i> (103×10 ⁶ /ml.)		
	Ex. 1	Ex. 4	Ex. 5	Ex. 1	Ex. 4	Ex. 5
25	tnc*	1,990	tnc	tnc	<10	8,500
	tnc	10	9,800	tnc	<10	160
	tnc	<10	<10	tnc	<10	110
	tnc	<10	<10	tnc	<10	90

*Too numerous to count.

It is evident that the compositions of Examples 2, 3, 4 and 5 illustrating several levels of added halogenated salicylic acids markedly increase the antibacterial effect on gram-negative organisms. The marked reduction in the number of gram-negative organisms is attributed to the presence of the halogenated salicylic acid and not to a possible synergistic action with hexachlorophene. This is illustrated by comparison of the compositions of Examples 1 and 6 in Table III.

TABLE III

Time following exposure (min.)	Number of survivors/ml. following exposure to—			
	<i>E. coli</i> (90×10 ⁶ /ml.)		<i>Ps. aeruginosa</i> (103×10 ⁶ /ml.)	
	Ex. 1	Ex. 6	Ex. 1	Ex. 6
50	tnc*	tnc	tnc	0
	tnc	80	tnc	0
	tnc	0	tnc	0
	tnc	0	tnc	0
	tnc	0	tnc	0
	tnc	0	tnc	0

*Too numerous to count.

In each of the following examples the composition of Example 1 was modified by the addition of the indicated acids:

Example No.	Acid	Concentration	
		Molar	Percent
7	Salicylic	0.01	0.14
8		0.031	0.43
9	5-chlorosalicylic	0.01	0.17
10		0.03	0.54
11	3,5-dichlorosalicylic	0.01	0.21
12		0.03	0.64
13	3,5-diiodosalicylic	0.01	0.39
14		0.031	1.21

The germicidal effectiveness of compositions incorporating the class of other halogenated salicylic acids (Exam-

3
ples 9-14) of the invention as compared to the compositions of Examples 1, 7 and 8 is illustrated in Table IV (0.01 molar in indicated acid) and Table V (0.03 molar in indicated acid).

3. A stable, non-soap cleansing composition in accordance with claim 2 containing from 0.1 to 1.0% by weight of 5-bromosalicylic acid.

TABLE IV

Time following exposure (min.)	No. of survivors/ml. following exposure to—									
	<i>E. coli</i> (74×10 ⁶ /ml.)					<i>Ps. aeruginosa</i> (103×10 ⁶ /ml.)				
	Ex. 1	Ex. 7	Ex. 9	Ex. 11	Ex. 13	Ex. 1	Ex. 7	Ex. 9	Ex. 11	Ex. 13
10	tnc*	tnc	tnc	tnc	tnc	tnc	tnc	tnc	27,300	3,700
30	tnc	tnc	tnc	8,500	1,930	tnc	tnc	tnc	70	1,060
60	tnc	tnc	22,700	680	20	tnc	tnc	tnc	30	740
180	tnc	tnc	<10	70	<10	tnc	tnc	20,300	10	620

*Too numerous to count.

TABLE V

Time following exposure (min.)	No. of survivors/ml. following exposure to—									
	E. coli (74×10 ⁶ /ml.)					Ps. aeruginosa (103×10 ⁶ /ml.)				
	Ex. 1	Ex. 8	Ex. 10	Ex. 12	Ex. 14	Ex. 1	Ex. 8	Ex. 10	Ex. 12	Ex. 14
10	tnc*	tnc	tnc	tnc	tnc	tnc	tnc	tnc	240	<10
30	tnc	tnc	tnc	31,000	5,400	tnc	tnc	35,400	<10	<10
60	tnc	8,500	1,850	200	50	tnc	tnc	4,700	<10	<10
180	tnc	<10	<10	<10	<10	tnc	tnc	440	<10	<10

*Too numerous to count.

I claim:

1. A stable, non-soap cleansing composition consisting essentially of an aqueous emulsion of alkylphenoxypolyalkylene ether sulfonate containing 0.1-1.0% by weight of a halogenated salicylic acid of the formula

wherein X is halogen and n is a number from 1 to 3, the amount of said sulfonate being between 10 and 20% of said composition by weight, said emulsion having a pH of 5-6.

2. A stable, non-soap cleansing composition in accordance with claim 1 in which the alkylphenoxy polyalkylene ether sulfonate is p-tertiary octylphenoxyethoxyethyl ether sulfonate.
